(No Model.)

P. MEDART.

MACHINE FOR GRINDING PULLEYS.

No. 256,440.

Patented Apr. 11, 1882.

AT TEST:

*Robert Burns.
J. Medart*

INVENTOR:

Philip Medart

UNITED STATES PATENT OFFICE

PHILIP MEDART, OF ST. LOUIS, MISSOURI.

MACHINE FOR GRINDING PULLEYS.

SPECIFICATION forming part of Letters Patent No. 256,440, dated April 11, 1882.

Application filed September 5, 1881. (No model.)

To all whom it may concern:

Be it known that I, PHILIP MEDART, a citizen of the United States, and a resident of the city of St. Louis, in the State of Missouri, have 5 invented certain new and useful Improvements in Machines for Grinding Pulleys, of which the following is a specification.

My invention relates to certain improvements in that class of grinding-machines used 10 for grinding off the face of belt-pulleys concentric to and parallel with their axes; and this invention consists in certain details of construction and arrangement of parts to effect the said purpose in an accurate, quick, and 15 effective manner, as will hereinafter more fully appear.

In the drawings, Figure 1 is a top plan; Fig. 2, a vertical section on a line through the axis of the pulley-carrying arbor; Fig. 3, an enlarged detail section through one of the guide-slides of the main frame; Fig. 4, an enlarged detail section transverse to Fig. 3.

Similar letters of reference refer to like parts in the several views.

As shown in the drawings, the machine consists of a rectangular bed or shears, A, supported on legs B, and provided with raised slides a, upon which the carriage C (that carries the pulley-arbor D) slides and is guided in 20 a line parallel with the face of the grinding-wheel E, the movement of the carriage being accomplished by a pair of feed-screws, c c', arranged at each side of the bed A, as shown, and geared together by means of chain-wheels c² c² and chain c³, or their equivalents, so as to turn in unison. c⁴ is a hand-wheel, by which the said feed-screws are operated. This improved construction entirely overcomes the difficulties to which an ordinary central feed-screw is liable, as follows: first, the difficulty of obtaining a perfect movement of the pulley-carrying carriage in a plane parallel with the axis of the grinding-wheel; second, the liability of the carriage being displaced from such position by an undue strain on the parts or an uneven wear of same, and, third, the liability of the carriage being forced out of line by the impact or strain of the grinding-wheel upon the pulley, all of which difficulties are 40 entirely overcome in a very effective manner by my improved construction.

The pulley-carrying arbor D is supported in bearings d d, as shown, and is capable of both an endwise movement (so as to feed the pulley across the face of the grinding-wheel E) and a 55 rotary movement in an opposite direction to that of the said grinding-wheel. The endwise movement is accomplished in the following manner:

D' is a box moving in slides on the overhanging or extension part C' of the carriage C, and operated by an endless feed-screw, c⁵, that is rotated by gear-wheels c⁶ c⁷, counter-shaft c⁸, and hand-wheel c⁹. The end of the arbor D is secured to and turns in the box D', so that 65 when any movement is imparted to the said box a like movement will in turn be imparted to the arbor D. At the opposite end to where it is attached to the box D' the carrying-arbor D overhangs the bed A, and is provided 70 with a head, d³, for the attachment of the pulley-carrying mandrel or chuck f, the attachment between the mandrel f and the head d³ being accomplished by the one screwing onto the other, or by means of any other well-known 75 means of attachment.

The advantages derived by making the attachment of the pulley (to be ground) to the attaching-head of the carriage-arbor, outside of the main frame, as shown, are as follows: 80 First, it allows for the grinding of a pulley of any required width of face; second, it permits of grinding a pulley of any required diameter without necessitating the use of a heavy and cumbersome machine; third, it forms a ready, 85 easy, and accurate means for the axial attachment of the pulley to be operated upon, and facilitates any required change in the size of the pulley-mandrel to suit the various sized bores of pulleys without necessitating the unshipping of any portion of the machine. 90

The rotary movement before mentioned is imparted to the arbor D by the following means:

d² is a stationary bevel-wheel arranged on the said arbor, and imparting a rotary motion 95 to it through a spline or feather engaging in a groove, d³, in the arbor, as shown, this construction being to permit of the necessary endwise movement of the arbor through the said bevel-wheel.

d⁴ is a driving-pinion for the bevel-wheel d², mounted upon a shaft, g, traveling with the 100

carriage C, and driven by a stationary pulley, G, the connection between the said pulley G and shaft g being by means of a spline and groove, so as to allow for the necessary end-wise movement of the shaft g through the pulley G. One of the supporting-boxes, g^3 , for the shaft g is arranged upon the carriage C, while the other, g^2 , is arranged upon the main bed or shears, as clearly indicated in Fig. 1.

10. It will be seen that by means of the gears c^6 c^7 and counter-shaft c^8 , the hand-wheels c^4 c^9 are brought into an adjacent position to each other, so that they will be convenient to the operator and enable him to effect the different movements of feeding the pulley toward and across the face of the grinding-wheel without changing his position.

The grinding-wheel E is arranged to one side of the bed or shears A, as shown, and one of its supporting-boxes, e, is arranged on said bed, while the other, e' , is arranged on the outer end of a bracket-frame, E', secured to the bed or shears A, as shown in Fig. 2.

25. The bracket-frame is of a bent form, as shown, so as to have a recessed portion, E², for the reception of the grinding-wheel, and such recessed portion may be arranged in either a vertical or horizontal position, as may be found most desirable or convenient.

30. Having thus fully described my said invention, what I claim as new, and desire to secure by Letters Patent, is—

1. In a machine for grinding pulleys, the combination of a pulley-carrying arbor having its end to which the pulley is attached overhanging the main frame, a grinding-wheel arranged to one side of the main frame, with its axis on a line parallel with the axis of the pulley-carrying arbor, and means for feeding the

pulley across the face of the grinding-wheel, 40 substantially as described.

2. In a machine for grinding pulleys, the arbor-carriage C, provided with an overhanging or extension part C', in combination with the carrying arbor D, box D', and feed-screw 45 c^5 , substantially as herein described, and for the purpose set forth.

3. In a machine for grinding pulleys, the combination of a pulley-carrying arbor having its pulley-carrying head overhanging the main 50 frame, a grinding-wheel arranged to one side of said frame with its axis on a line parallel with the axis of the pulley-carrying arbor, an arbor-carriage, C, and duplicate operating-screws c^6 , arranged at the sides of the main 55 frame, and connected together so as to operate in unison, for the purpose set forth.

4. A machine for grinding pulleys, consisting of a bed or shears, A, arbor D, feed-screws c^6 c^7 , and grinding-wheel E, in combination 60 with the traveling shaft g, driving-pulley G, gears d^2 d^4 , box D', and feed-screw c^5 , all arranged substantially as described, and for the purpose set forth.

5. A machine for grinding pulleys, consisting of a bed or shears, A, grinding-wheel E, carriage C, feed-screws c^6 c^7 , chain-wheels c^2 , chain c^3 , hand-wheel c^4 , arbor D, box D', feed-screw c^5 , gears c^6 c^7 , counter-shaft c^8 , hand-wheel c^9 , gears d^2 d^4 , traveling shaft g, and driving-pulley G, all arranged substantially as herein 70 described, and for the purpose set forth.

In testimony whereof witness my hand at St. Louis, Missouri, this 2d day of September, 1881.

PHILIP MEDART.

In presence of—

ROBERT BURNS,
WM. MEDART.
